CLAIM

An ornamental design for a box with doll lid, as shown and described.

DESCRIPTION

FIG. 1 is a right side perspective view of a first embodiment of a box with doll lid showing the new design;

FIG. 2 is a front view thereof.

FIG. 3 is a rear view thereof.

FIG. 4 is a right side view thereof.

FIG. 5 is a left side view thereof.

FIG. 6 is a top plan view thereof.

FIG. 7 is a right side perspective view of a second embodiment of the box with doll lid.

FIG. 8 is a front view thereof.

FIG. 9 is a rear view thereof.

FIG. 10 is a right side view thereof.

FIG. 11 is a left side view thereof; and,

FIG. 12 is a top plan view thereof.

The broken lines depict portions of the box with doll lid that form no part of the claimed design.
